Primary Examiner—A. Hugo Word*Assistant Examiner*—Doris Clark*Attorney, Agent, or Firm*—Charles W. Chandler[57] **CLAIM**

The ornamental design for a transparent screen protector, as shown and described.

DESCRIPTION

FIG. 1 is a perspective view of a transparent screen protector showing my new design; the broken line showing a door is for illustrative purposes only and form no part of the claimed design;

FIG. 2 is a left end elevational view thereof;

FIG. 3 is a cross sectional view taken along line 3—3 of FIG. 1;

FIG. 4 is a top plan view thereof;

FIG. 5 is a front elevational view thereof; and,

FIG. 6 is a bottom plan view thereof.

FIG. 2

FIG. 3

FIG. 4

FIG. 5

FIG. 6
